(57) **CLAIM**

The ornamental design for a squeegee and scrubber bar tool,
as shown and described.

DESCRIPTION

FIG. 1 is a perspective view of a squeegee and scrubber bar tool,
showing our new design, in a first position;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a perspective view thereof;

FIG. 9 is a perspective view of a squeegee and scrubber bar
tool showing our design in a second position;

FIG. 10 is a front view thereof;

FIG. 11 is a rear view thereof;

FIG. 12 is a left-side view thereof;

FIG. 13 is a right-side view thereof;

FIG. 14 is a top view thereof;

FIG. 15 is a bottom view thereof; and,

FIG. 16 is a perspective view thereof.

The broken lines depict portions of the article that form no
part of the claimed design.

1 Claim, 14 Drawing Sheets
